PUMP

Harold E. Adams, South Norwalk, Conn., assignor
to Nash Engineering Company, South Norwalk,
Conn., a corporation of Connecticut

Application August 2, 1940, Serial No. 349,953

22 Claims. (Cl. 103—6)

This invention relates to fluid pumps, and more particularly to a pump organization designed to handle both liquids and gases, wherein centrifugal pumping means are provided for handling liquids, and liquid piston means are provided for the pumping of gases, in conjunction with the liquids being pumped by the centrifugal means.

It has been the practice in the past to use entirely separate pumps for handling liquids and gases, these pumps not necessarily operating at the same rotative speed. A later improvement was made so that both pumping means could operate at the same rotative speed and the two units could be coupled together and driven by a common driver.

Subsequently, in order to reduce costs and conserve space for the pumping equipment, manufacturing practice brought about a change in the design of pump casings and a shortening of the drive shafts in order to move the several pumping units closer together. This has been favorably accepted in the trade, and has resulted in the use of a common casing, as well as a common drive shaft for the multiple units, the respective impellers, however, being separated by partitions in the casings, dividing same into independent pump chambers for each unit.

The patented art is replete with typical instances of past and present designs of pump casings, and present day practice utilizes very compact multiple unit pumps having a centrifugal and a liquid ring pump separated from each other by a partition wall in a common casing, the impellers being mounted on a common drive shaft. This, of course, necessitates a seal between the pumping units at the point where the drive shaft passes through the stationary partition wall. Such constructions, when first developed constituted a considerable advance in pump manufacture and practice at the time of such development, especially when it is considered that the previous practice consisted in employment of separate, independent casings spaced from each other, even though a common drive shaft may have been used.

It is a primary object of the present invention to carry this combination still further in a novel, yet very successful, arrangement that combines the liquid and gas rotating members into a single unit as well as utilizing a single pump casing and compartment, thus reducing the size and cost of the unit.

Another object is to form the partition wall be-

5 impeller member, one side of which functions to pump gases and the other side of which handles liquids.

Another feature of the present invention is to devise a construction using a combination liquid and gas pump reduced to a single unit.

Another advantage of the present invention resides in the design of the pump casing and pumping member to effect a novel seal between the pump chambers at points remote from the drive shaft.

A still further feature of the present invention is to provide for increased efficiency through the reduction of hydraulic losses in the overall unit and at the same time produce a very material reduction in manufacturing costs.

To the attainment of the foregoing and other objects which will hereinafter appear as the description proceeds, reference may be made to the accompanying drawings, wherein:

Figure 1 is a sectional elevation through a pump assembly, showing an adaptation of the present invention and is taken substantially on the line 1—1 of Figures 2 and 3.

Figure 2 is a sectional view through the pump assembly taken substantially on the line 2—2 of Figure 1.

Figure 3 is a sectional view through the pump assembly taken substantially on the line 3—3 of Figure 1.

Figure 4 is a part sectional view showing a seal arrangement modified with respect to Figure 1 and using a relief valve.

Figure 5 is a part sectional view showing a seal arrangement modified with respect to Figures 1 and 4 using an orifice in the pipe line.

Figure 6 is one face view of the pumping element shown in Figure 7.

Figure 7 is a diametric section through a form of pumping element or rotor as adapted for the present invention.

Figure 8 is the other face view of the pumping element or rotor shown in Figure 7.

Figure 9 is one face view of the liquid pumping element shown in Figure 10.

Figure 10 is a diametric section through a form of liquid pumping element as used in accepted practice of multiple pump assembly, and as used in the modification shown in Figure 13.

Figure 11 is a diametric section through a form of gas pumping element as used in accepted practice of multiple pump assembly, and as used in the modification shown in Figure 13.

Figure 12 is one face view of the gas pumping element shown in Figure 11.

Figure 13 is a sectional view through a multiple pump assembly illustrating a modification of accepted practice of constructing pump organizations, in accordance with the present invention.

Figure 14 is a sectional view of a combined impulse and liquid ring pump taken on the line 14-14 of Figure 15, and

Figure 15 is a sectional view thereof taken on the line 15-15 of Figure 14.

Referring now, more specifically to the drawings, wherein like reference numerals indicate like parts, H indicates a pump housing of a particular type used with the liquid pumping section selected for the purpose of illustrating the invention. H¹ indicates the housing for the gas pumping section. S indicates a separating tank of the pump assembly wherein particles of liquid are removed from the gas discharged from the gas pump.

M indicates a prime mover in the form of an electric motor, mounted on the pump housing, as shown in Figure 1, and this motor drives the rotary drive shaft 17. In the preferred form of the invention, the shaft 17, as illustrated, is disposed on a horizontal axis, but it is to be understood that the principle of the invention will function as well with the shaft disposed on a vertical axis, or any angular disposition between the vertical or horizontal axis, should the requirement of any such unusual installation be specified.

In the form of the housing H selected to illustrate one adaptation of the invention, the volute portion 18 of the pump casing H is preferably cast or molded integral with one of the partition walls 19 to define a pumping compartment. However, it is to be understood that the present invention is in no way limited to this particular construction, for the pump compartment may be made separate from the housing H, in which event it would be self-supporting; or it may be made separate and attached to any device for which its peculiar function of pumping liquid and gas simultaneously is adapted.

In all forms of the present invention, the rotating pumping member that carries the pump elements, divides the compartment formed by the assembled parts of the housing H-H¹, into separate pump chambers. Each chamber has a set of passages including an inlet and an outlet passage. In Figure 1, the parts of the pump casing or housing H-H¹ in the assembled relation, form the pumping compartments 21 and 20. These compartments are divided by the rotating pumping member P. The rotating pumping member P consists of a central supporting disc 42, on one face of which are carried the centrifugal liquid pump elements 45, and the elements 46 which function as the liquid ring gas pump are carried by the opposite side of the disc 42, thereby creating a unitary or combination impeller-rotor.

The centrifugal pump elements operate in the pump chamber 21, and in the other chamber 20 the liquid ring gas pump elements operate, and of course, each chamber is provided with an inlet and an outlet passage.

In the form of the pump casing H shown in Figure 1 of the drawings, the volute portion or head of the casing is indicated at 18. Around the inside of the head part 18, near the periphery, is the volute passage or compartment 21 75

which is the discharge for the centrifugal liquid pump. The liquid ring pump housing H¹ is secured at its marginal portion by the bolts 22 in depending relation to the volute or head 18.

5 The pumping member P shown in detail in Figures 1, 6, 7 and 8 of the drawings, is a combined impeller-rotor and comprises a central supporting disc 42 which carries on one face the impeller elements 45 for the centrifugal pump, while on the opposite face are carried the rotor elements or vanes 46 which constitute the rotor of the liquid ring type of pump.

The center of the disc 42 merges with an outstanding hub 43 keyed to the drive shaft 17, 15 which is driven by the motor M, and the disc is secured to the drive shaft by means of the nut 44. The impeller blades 45 forming the pumping elements for the centrifugal liquid pump and the vanes 46 for the liquid ring pump are preferably cast or molded integral with the disc 42.

On the face of the disc remote from the blades 45 is a ring-like lip 47, the outer edge of which conforms in shape to a lip 50 on the housing H¹, 25 but there is a slight clearance between the two surfaces to form a liquid seal 25.

At each end of the blades 46 are concentric ring-like depending lips 48. The outer face of the lips 48 conform in shape with confronting lips 51 on the side walls of lobe chamber 20, but there is a tolerable clearance between these confronting faces to form liquid seals 23 and 24 preventing leakage of any gas from the gas pump. The vanes 46 terminate short of the center of 30 the disc 42 to form an inverted cup-like cavity 52^a mating with the frusto-conical port member 52.

The passages 53 of the centrifugal impeller of the pumping member P are confined between the 40 shroud plate 54 and the confronting face of the disc 42, and these passages are bounded laterally by adjacent blades 45.

The buckets or displacement chambers 55 for the rotor of the liquid ring part of the pumping member P are confined between the shroud 56 and the confronting face of the disc 42 and they are bounded laterally by the adjacent vanes 46. The shrouds 54 and 56 are round plates that may be secured to the blades or cast integrally with 50 the pumping element to the lower edges of the vanes. In fact, with some constructions the shrouds may be omitted, the present showing being of course, merely illustrative.

The principle of operation of a liquid ring gas pump is well known in the art and consists of using a liquid piston in the outer portions of the buckets or displacement chambers 55. As the member P rotates, the liquid piston moves out and in of the buckets by centrifugal force and reaction in the lobe passage 20 and the land 57, Figure 2, whereby gas in the inner ends of the buckets is withdrawn from the inlet passage 41, through the inlet port 58 in the port member 52, and is compressed in chambers 55 and expelled through the outlet port 59, in the member 52 from where it is discharged into the outlet passage 60. Gas enters the inlet passage 41 through a pipe 38, and is discharged through the outlet passage 60 and pipe 61 to separator 32 wherein any sealing liquid used in the liquid ring pump, which may have become entrained in the discharging gas, is separated and returned to the system through the ball float valve 34, or the connections 31-33, hereinafter described. The

gas is discharged from the separator through the pipe 62.

In the illustrative embodiments herein, a gas pump having a single eccentric lobe or displacement chamber is shown, largely for simplicity. The liquid piston pump, however, referred to is not restricted to this type but may include pumps having several eccentric lobes and with corresponding multiple sets of inlet and outlet ports. The construction of the liquid pump may also vary considerably from that shown and may be any of the numerous designs in use. For example, Figure 1 illustrates a pump of the centrifugal type, while Figures 14 and 15 show a pump of the impulse type, exemplified by the patent to Jennings 2,073,014.

Referring now to the unitary construction of this invention as shown in Figure 1, it is pointed out that the central driving disc 42 in effect replaces the conventional stationary side wall or partition of a liquid pump casing, which may also form the stationary side wall of a gas pump casing, while at the same time forming a common rotating disc in place of the usual impeller shroud 68 of the liquid pump and 78 of the gas pump (Figures 10, 11 and 13). A material increase in efficiency, due to reduced friction losses, is thus effected by the impeller-rotor construction of Figure 1, for friction losses between the rotating liquid in the gas pump with its side wall have been entirely eliminated. The friction losses between the rotating liquid in a liquid pump casing with its side wall are materially reduced and in addition to this, the friction loss of a rotating shroud such as 78 of the gas pump, and a large portion of the friction loss of the rotating shroud 68 of the liquid pump, are entirely eliminated. It is thus evident that the combining of the gas and liquid impellers in one element effects a material increase in efficiency as well as the reduction of space and costs.

This innovation of combining such dissimilar elements in one rotating member is made possible by various sealing arrangements, to be described that enable the gas pump and the liquid pump to operate satisfactorily in such close relationship.

The performance of liquid pumps, as is well known in the art, is susceptible to inefficiency caused by traces of gas being mixed with the liquid, such a mixture resulting in the breaking down of the centrifugal action, due to the presence of lighter gas bubbles. On the other hand, a gas compressor is very sensitive to the quantity of liquid seal induced into its chambers. An insufficient amount of seal or an excess amount of seal may result in the breakdown of its performance. Some of the features forming a part of this invention for the segregation and control of these two dissimilar fluids may be described as follows:

As a general thing it is assumed that under normal operating conditions, the liquid pump is assured of a supply of liquid at the inlet to this pump, the presence of this liquid being assured, if necessary, by automatic float control of the discharge, or a pressure relief valve located in the discharge, or other similar means where there is a possibility of the suction side being uncovered due to a limited supply of liquid. It is also assumed that the discharge pressure of the liquid pump is at an equal or higher absolute pressure than the discharge pressure of the gas pump or compressor. In many cases the absolute pressure at the suction side of the liquid pump corresponds to the absolute pressure at the inlet of the gas

pump or compressor. This latter condition, however, is not arbitrary.

The gas pump or compressor may operate either as a vacuum pump, where its normal discharge pressure would be atmospheric, or it may operate as a gas compressor over any usual pressure range compatible with its design and proportions.

It is furthermore assumed that the gas pump or compressor is sealed with the same type of liquid that is being pumped by the liquid pump itself, in fact primary seals will be effected by liquid from the centrifugal side, under the pressures of the centrifugal pump. Make-up sealing liquid can be introduced into the gas pump or compressor by any of the conventional methods now used. In the drawings one method is illustrated as at 84, of introducing auxiliary or make-up sealing liquid into the inlet of the gas pump for the purpose of sealing various points of clearance within the gas pump and compensating for any losses in the original seal.

It will be noted that an annular chamber 26 is formed between the two sealing surfaces 24 and 25. An orifice 27 communicates between the annular chamber 26 and the outer chamber 28, this chamber being an irregular space formed between the outer wall 29 of the liquid ring pump housing and the enclosing wall 30.

If the pressure in the annular chamber 26 is materially higher than the discharge pressure of the liquid ring pump, it will force an excessive amount of sealing liquid through the sealing surfaces at 24 and overload the liquid ring pump end with an unnecessary amount of sealing liquid, with resultant increased load and lowered efficiency of this unit.

Provision is made by this invention to limit the formation of excessive pressure about the sealing surfaces 24. The impeller-rotor combination may be made with impeller diameters and rotor diameters of widely varying values, according to the particular service to which they are applied. The liquid ring pump rotor diameter is varied to suit the rotational speed of the driving motor to give the required peripheral velocity to the outer diameter of this rotor. The required peripheral speed of the liquid impeller, however, may vary widely according to the pressure at which it may be designed to deliver the liquid. This, therefore, requires a specific diameter of liquid impeller for each designed pressure service.

It may be seen that the designed pressure difference between the volute passage 21 and the lobe chamber 20 may vary over a wide range.

It will be noted, therefore, that if only one sealing surface were provided, such as 24 between the lobe chamber 20 and volute passage 21, there would be a wide variation in the requirements for maintaining tightness at this point. A sufficiently tight joint here might be provided but it might conceivably be difficult to maintain over years of service. This seal could be maintained by the use of a replaceable seal but a better method of controlling the pressure difference across the seal 24 is indicated.

The primary sealing rings or lips with sealing surfaces at 25 have been supplied, which take care of the initial pressure drop from the volute passage 21 to the annular ring chamber 26. The relief orifice 27 relieves the leakage that thus enters the annular chamber 26, draining this excess leakage into the chamber 28. The sealing liquid entering chamber 28 is drained off through other control means as hereinafter described, the meth-

od being to regulate the pressure in chamber 28 such that a fairly constant pressure is maintained in the annular chamber 26 and hence on the sealing surfaces at 24, of the liquid ring pump rotor. For the regulation of pressures in the intermediate chamber 28, several alternative means may be employed, according to the particular structures involved, illustrations of several alternatives being shown in Figures 1, 4, 5, 14 and 15.

In the method of control of pressure in chamber 28, Figure 1, there is provided a connection 31 in communication with the separator chamber 32 by a connection 33. The separator chamber 32 during the normal operation of the pump is at the discharge pressure of the gas compressor or vacuum pump and is fairly constantly maintained at this pressure.

It will thus be seen that with the inter-connection of chambers 28 and 32, the liquid relieved from the annular space 26 through the orifice 21 will be bled off into the chamber 32 and essentially keep chamber 26 slightly above the discharge pressure of the gas compressor. The excess leakage liquid bled off by orifice 21 after delivery into the separator 32 will be returned through the float valve 34 back into the inlet side of the structure at 35. By these means a fairly constant desired pressure, slightly in excess of the gas compressor discharge, will be maintained in the annular space 26 and the sealing surfaces 24.

Should the discharge pressure of the liquid pump drop below that of the gas pump, the pressure in chamber 26 will not drop materially below the gas pump discharge pressure, due to the presence of the liquid at discharge pressure in chamber 28, thus maintaining the necessary liquid seal at 24.

Stated somewhat in other language, the liquid in the chamber between the liquid ring impeller and the centrifugal impeller is maintained at a pressure approximately equal to the discharge pressure of the liquid ring pump for the purpose of promoting and maintaining a seal between the clearance spaces of the liquid ring impeller, as well as between the liquid ring and centrifugal pumping units. In this connection, the seal, maintained by the discharge pressure, is somewhat similar to the principles described in the patent to Adams, No. 2,195,395.

Additional means, embodying these principles, are provided to ensure a liquid seal at sealing surfaces 23 and 36, by the addition of an orifice 37 communicating with these sealing surfaces 23 and 36 from chamber 28. The orifice 37 is provided to limit the seal supply to the above sealing surfaces to the desired amount.

A variation of the above control of pressures in chamber 28 is accomplished by bleeding off the leakage into this chamber through pipe 31 to the inlet side of the liquid pump as at 35, as shown in Figure 5. In this case a suitably sized orifice 39 would be provided to prevent the lowering of the pressure in 28 from approaching that of the inlet side of the compressor, as this complete lowering of pressure would be detrimental, in that it might not maintain sufficient seal pressure in the annular chamber 26 for the proper sealing at the surface 24. This latter connection at 35 would be resorted to in cases of combinations using impellers for extremely high delivery pressure in the volute passage 21 where greater leakage might be expected and where such leak-

age might be greater than the capacity of the float control valve 34.

Another alternate method of controlling the pressure in chamber 28 is shown in Figure 4. This is effected by the use of a relief valve 40 which may be placed either to relieve chamber 28 in lieu of the free orifice 21, or to relieve the chamber 28 through pipe 31. The pressure maintained in chamber 28 and consequently chamber 26 would be regulated by the relieving action of the spring controlled relief valve 40. The relief valve 40 shown is a typical automobile tire valve and such a relief valve may be used on very small pumps.

The invention is not limited, however, to this particular type of valve as larger valves would be required on larger pumps. Any relief valve arrangement tending to maintain a substantially constant pressure or a substantial pressure difference in chamber 28 by bleeding off liquid through the relief valve and pipe 31 to the low pressure side of the pump chamber 75, as at connection 35, can be used.

When using such a relief valve, the orifice 39 in the pipe 31 as shown in Figure 4 would not be used.

In Figures 9 and 10 there is illustrated a centrifugal impeller for a liquid pump as used in accepted practice of constructing multiple pump assemblies, while in Figures 11 and 12 is shown a rotor for a liquid ring pump assembly, as similarly used. Accepted practice, as heretofore stated, may involve the use of these two types of impellers in a single unit on a common drive shaft, and in a common housing, the impellers, however, being separated by partitions forming independent pump casings.

By comparing the dual impeller illustrated in Figures 1, 6, 7 and 8, with the two impellers of Figures 9 to 12, the advantages of the present invention, including increased efficiency, compactness, saving in manufacturing costs of the impeller elements and associated structures, will be at once apparent.

However, under some circumstances, it may be desirable to utilize the principles of this invention with separate impellers, in structures similar to present accepted practices.

Figure 13 illustrates an adaptation of a pump organization as used in accepted practice of multiple pump design, but wherein the principles of the present invention are employed. Instead of using a composite impeller wherein the liquid pump, and gas pump impellers are formed as a unitary construction with the equivalent of a partition wall built into the dual impeller, the separated impeller elements shown in Figures 9 to 12 are employed, but the customary partition between the pump chambers is removed. This requires some means of sealing the gas pump chamber from the liquid pump chamber.

In this embodiment the liquid pump impeller 63 is constructed with a circumferential lip 64 outstanding from the driving disc 65. The outer edge of this lip conforms in shape to the replaceable ring 66 in casing 67, but there is a clearance between the two surfaces to form a liquid seal 68, corresponding in function to the seal 25 of Figure 1.

The hub 70 of the gas pump rotor 69 is extended toward the impeller 63.

The casing 67 is extended to include the body of the gas pump including lobe displacement chamber 76 and a head section 83, somewhat sim-

ilar to head section H^1 of the unitary construction shown in Figure 1.

The rotor 69 is an independent member mounted on the end of the common drive shaft. It is thus seen that there is, in effect a separate liquid impeller and casing and a separate gas impeller and casing built in unitary construction, with the impellers driven by a common drive shaft.

The chamber 26¹ corresponds in function to the chamber 26 of Figure 1, and the chamber 28¹ similarly corresponds to the chamber 28 of Figure 1, although obviously the proportions are different. Between the chambers 26¹ and 28¹ is the restricted orifice 27¹, corresponding to orifice 27, and extending from the chamber 28¹ is 15 a passage 37¹ which corresponds to the orifice 37 cooperative with the sealing surfaces 23 and 36.

In this form, one shroud of the gas pump rotor will be sealed, as indicated at 23¹ and 36¹ in a manner comparable to seals 23 and 36 of Figure 1, and the other shroud will be sealed as indicated at 71, in a manner equivalent to the seal 24, and the chambers 26¹ and 28¹, together with the passages and orifices 27¹ and 37¹ cooperate to maintain the proper pressures at the sealing surfaces, just as described in connection with Figure 1.

The connections 31 and 33 from the separator (not shown), as well as the connection 35 are the same as in Figure 1.

It might be noted, in the description of this figure, that where the elements are identical with those shown in other figures, the same numerals have been used, but where the elements are structurally somewhat different, even though equivalent, primed or wholly new numerals have been used.

Obviously, various modifications in the mode of sealing between the two pump casings may be provided, within the scope of this invention, examples of such variations being found in Figures 4 and 5, previously described.

Referring now to Figures 14 and 15, it will be seen that the invention is not confined to the combination of a centrifugal liquid pump with a gas pump of the liquid ring type, but that other forms of liquid pump such as a pump of the impulse or "scraper" type may be used, for handling liquids at high pressures.

In other words, the impulse type of impeller will develop much higher discharge pressures for a given diameter and speed than a centrifugal pump of the same diameter and speed, and the application of the invention to a pump as shown in Figures 14 and 15 is particularly desirable in some usages, such as heating systems, where small quantities of liquids must be delivered against high pressures, as compared with the type of usage for which the previously described forms of the invention are readily adaptable.

The gas pump portion of the unit shown in this embodiment is identical with that disclosed in Figure 1, and no further description thereof is necessary, the same reference numerals having been used. The general construction of the liquid pump portion of this unit is substantially that disclosed in the Jennings patent, No. 2,073,014, except that in this instance the impeller has been combined unitarily with the rotor of the gas pump, and the central driving disk portion of the dual impeller made to function, by cooperation of the sealing means provided, as a movable partition wall, just as in the earlier described forms of the invention.

Since the mode of operation of the liquid pump portion of the unit is well known, thoroughly de-

scribed in said patent, and forms no material part of the instant invention, reference may be made to that patent for a detailed description thereof. Suffice to say, that the pump comprises generally a housing 86 which mates with the gas pump housing H^1 , and is provided with an inlet 81 and an outlet or discharge connection 88.

The inlet connection 81 communicates through a channel 89 with an opening 90 immediately adjacent the operating buckets or chambers 91 formed by impulse blades 92 on the impeller or rotor 93. The buckets are enclosed at their sides by the central driving disk 42 which forms a common wall between the rotor of the gas pump and the impeller of the liquid pump, and the shroud 94.

In operation, the liquid is carried around from the inlet opening 90 through the volute chamber 95, under the circulating impulse action of the blades 92, and where, by this action, the pressure on the liquid is built up to that of the desired discharge. The liquid is ejected from the impulse wheel or impeller 93 into the passage 96, from whence it passes into the discharge chamber 87, being finally discharged at the outlet 88.

In order to apply the principles of the present invention to a pump of the impulse type, as well as to the combination of such a pump with a gas pump rotor, seals are provided at the points 98 and 99, thus making it possible to retain the liquid being pumped, at high pressure between the impeller wheel 93 and the volute 95. The seals are provided by cooperating sealing surfaces in the manner described in Figure 1, the liquid seal 99 corresponding to the seal 25 of Figure 1, and the seal 24 being, of course, identical with that shown in Figure 1. The additional seal 98, in cooperation with the seal 99, represents an improvement in impulse type pumps, as conventionally known.

It will be understood that while the type of pump illustrated in the aforesaid Jennings patent, No. 2,073,014 has been described herein as an adaption of a liquid pump which might be used in the combination, that this description is not intended as limiting, as various other turbine or impulse types may be used. Further, practically in all respects the combination of this liquid impeller with the gas pump as shown in these figures is the same as the combination between the centrifugal pump impeller and the gas pump illustrated in the early described figures, the principal difference being in the characteristics of the liquid pump portion of the unit.

Similarly variations in the type of liquid ring pump are contemplated, as within the scope of the invention, the herein-described embodiments being primarily illustrative. While the gas pump illustrated herein is provided with conical port members, it is quite obvious that many modifications will occur to those skilled in the art. For example, the liquid ring pump might be of the type which is provided with cylindrical port members, or with a side port member, as distinguished from a cone or a tapered port member.

From the foregoing, the operation of the various embodiments of the invention herein shown will be clear. The gas pump portion will function in its conventional and normal manner, and the liquid pump portion will likewise function as conventionally intended, but by the sealing principles applied, it is made possible to produce an extremely compact, highly efficient unit, preserving, with a combined impeller, the individual

characteristics of each pump. The main or central driving disk portion of the dual impeller unit acts as the main dividing wall or partition between the two pumps, the normal running clearance between said moving partition wall and the pump housing being cared for by the several seals.

Also, it is obvious that regardless of the types of pump which are utilized, the principles of the invention may be applied even if the impellers are separated, just as in the described embodiment of Figure 13.

Having thus fully described my invention, what I claim as new and desire to secure by Letters Patent of the United States is:

1. In a unitary centrifugal liquid pump and liquid ring gas compressor including a casing, a common unitary impeller therein adapted to handle liquid at one side of the pump-compressor and gas at another side of the pump-compressor, and means for creating and maintaining a liquid seal between said liquid and gas sides, at a pressure essentially that of the pressure in the discharge of the gas side.

2. In a unitary centrifugal liquid pump and liquid ring gas compressor, a common unit casing divided to provide regions for the handling of liquid and gas, means to pump liquid and compress gas therein, and means for creating and maintaining a liquid seal between said regions at a pressure essentially that of the pressure in the discharge of the gas region.

3. In a unitary liquid pump and gas compressor, a common unitary impeller adapted to handle liquid at one side of the pump-compressor and gas at the other side thereof, means for creating a liquid seal between said liquid and gas sides, and means to maintain said seal at a pressure essentially that of the pressure in the discharge of the gas side.

4. In a unitary liquid pump and liquid ring gas compressor, a common unit casing divided to provide regions for the handling of liquid and gas, means to pump liquid and compress gas therein, means to pump liquid and compress gas therein, including liquid ring displacement chambers cooperative with the liquid ring of the gas compressor, means for creating a liquid seal between said regions, and means for maintaining said seal at a pressure essentially that of the pressure in the discharge of the gas region.

5. In a unitary liquid pump and liquid ring gas compressor, a common unit casing providing regions for the handling of liquid and gas, means in said casing to pump liquid in the liquid region, means also in said casing to compress gas in the gas region, including liquid ring displacement chambers cooperative with the liquid ring of the gas compressor, and means for creating and maintaining a liquid seal between said pumping and compressing means at a pressure essentially that of the pressure in the discharge of the gas region.

6. In a unitary liquid pump and liquid ring gas compressor, a common unit casing providing regions for the handling of liquid and gas, means in said casing to pump liquid in the liquid region, separate means also in said casing to compress gas in the gas region, including liquid ring displacement chambers cooperative with the liquid ring of the gas compressor, means for creating a liquid seal between said pumping and compressing means, and means for maintaining said seal at a pressure essentially that of the pressure in the discharge of the gas region.

7. In a unitary impulse type liquid pump and liquid ring, gas compressor, a common unitary impeller adapted to handle liquid at one side of the pump compressor and gas at another side thereof, means including sealing surfaces on the liquid side of the impeller for creating and maintaining a liquid seal between said liquid and gas sides at a pressure essentially that of the pressure in the discharge of the gas side.

10 8. In a unitary centrifugal liquid pump and liquid ring gas compressor including a casing, a common unitary impeller therein adapted to handle liquid at one side of the pump-compressor, and gas at another side of the pump-compressor, and means for creating and maintaining a liquid seal between said liquid and gas sides at a desired intermediate pressure between that of the pressure in the discharge region of the liquid pump and that of the pressure in the discharge region of the gas compressor.

15 9. In a unitary centrifugal pump and liquid ring gas compressor including a casing, a common unitary impeller therein adapted to handle liquid at one side of the pump-compressor, and gas at another side of the pump-compressor, means for creating and maintaining a liquid seal between said liquid and gas sides, at a desired intermediate pressure between that of the pressure in the discharge region of the liquid pump 20 and that of the pressure in the discharge region of the gas compressor, and for creating and maintaining a liquid seal between said liquid and gas sides, at a pressure essentially that of the pressure in the discharge of the gas side.

30 10. In a unitary centrifugal pump and liquid ring gas compressor, a common unit casing divided to provide regions for the handling of liquid and gas, means to pump liquid and compress gas therein, means for creating and maintaining a liquid seal between said regions at a desired intermediate pressure between that of the pressure in the discharge region of the liquid pump 35 and that of the pressure in the discharge region of the gas compressor, and for creating and maintaining a liquid seal between said regions at a pressure essentially that of the pressure in the discharge of the gas region.

40 11. In a unitary liquid pump and liquid ring gas compressor, a common unitary impeller adapted to handle liquid at one side of the pump-compressor and gas at the other side thereof, means for creating a liquid seal between said liquid and gas sides, and means to maintain said seal at a desired intermediate pressure between that of the pressure in the discharge region of the liquid pump 45 and that of the pressure in the discharge region of the gas compressor, and for creating and maintaining a liquid seal between said regions at a pressure essentially that of the pressure in the discharge of the gas region.

50 12. In a unitary impulse type liquid pump and liquid ring, gas compressor, a common unitary impeller adapted to handle liquid at one side of the pump compressor and gas at another side thereof, means including sealing surfaces on the liquid side of the impeller for creating and maintaining a liquid seal between said liquid and gas sides at a desired intermediate pressure between that of the pressure in the discharge region of the liquid pump and that of the pressure in the discharge region of the gas compressor, and for maintaining a part of said seal at a pressure essentially that of the pressure in the discharge of the gas side.

60 13. In a unitary centrifugal liquid pump and liquid ring gas compressor including a casing, a common unitary impeller therein adapted to

handle liquid at one side of the pump-compressor, and gas at another side of the pump-compressor, a seal chamber between said liquid and gas sides, and means for creating and maintaining a liquid seal in said chamber at a pressure essentially that of the pressure in the discharge of the gas side.

14. In a unitary centrifugal liquid pump and liquid ring gas compressor including a casing, a common unitary impeller therein adapted to handle liquid at one side of the pump-compressor, and gas at another side of the pump-compressor, a seal chamber between said liquid and gas sides, and means for creating and maintaining a liquid seal in said chamber at a desired intermediate pressure between that of the pressure in the discharge region of the liquid pump and that of the pressure in the discharge region of the gas compressor.

15. In a unitary centrifugal liquid pump and liquid ring gas compressor, a common unit casing divided to provide regions for the handling of liquid and gas, means to pump liquid and compress gas therein, a seal chamber between said liquid and gas regions, and means for creating and maintaining a liquid seal in said chamber at a pressure essentially that of the pressure in the discharge of the gas region.

16. In a unitary centrifugal liquid pump and liquid ring gas compressor, a common unit casing divided to provide regions for the handling of liquid and gas, means to pump liquid and compress gas therein, a chamber between said liquid and gas regions, and means for creating and maintaining a liquid seal in said chamber, at a desired intermediate pressure between that of the pressure in the discharge region of the liquid pump and that of the pressure in the discharge region of the gas compressor.

17. In a unitary liquid pump and gas compressor, a common unitary impeller adapted to handle liquid at one side of the pump-compressor and gas at the other side thereof, a chamber between said liquid and gas sides, means for creating a liquid seal in said chamber, and means to maintain said seal at a pressure essentially that of the pressure in the discharge of the gas side.

18. In a unitary impulse type liquid pump and liquid ring gas compressor, a common unitary impeller adapted to handle liquid at one side of the pump-compressor and gas at another side thereof, means including sealing surfaces on the liquid side of the impeller and sealing surfaces on the interior of the casing for forming a seal chamber, and means to create and maintain a liquid seal in said chamber at a pressure essentially that of the pressure in the discharge of the gas side.

19. In a unitary impulse type liquid pump and liquid ring gas compressor, a common unitary

impeller adapted to handle liquid at one side of the pump-compressor and gas at another side thereof, means including sealing surfaces on the liquid side of the impeller and sealing surfaces on the interior of the casing for forming a seal chamber, and means to create and maintain a liquid seal in said chamber at a desired intermediate pressure.

20. In a unitary centrifugal pump and liquid ring gas compressor, a common unit casing divided to provide regions for the handling of liquid and gas, means to pump liquid and compress gas therein, a plurality of seal chambers between said liquid and gas regions, means for creating and maintaining a liquid seal in one of said chambers at a pressure essentially that of the pressure in the discharge of the gas region and for creating and maintaining a liquid seal in another of said chambers at a desired intermediate pressure between that of the pressure in the discharge region of the liquid pump and that of the pressure in the discharge region of the gas compressor.

21. A pump comprising a pump casing provided with a compartment including a rotating disc or partition wall traversing the compartment and dividing said compartment into separate pump chambers, said disc having typical centrifugal pump blades on one side and extending into one of these pump chambers to operate as a typical centrifugal liquid pump and having on the opposite side of said disc forward curved rotor blades forming rotating displacement buckets which operate in the other pump chamber to pump and compress gas therethrough by the displacing action of these blades cooperating with a liquid ring operating eccentrically in said other pump chamber.

22. A pump comprising a pump casing provided with a compartment including a rotating disc or partition wall traversing the compartment and dividing said compartment into separate pump chambers, said disc having typical centrifugal pump blades on one side and extending into one of these pump chambers to operate as a typical centrifugal liquid pump and having on the opposite side of said disc forward curved rotor blades forming rotating displacement buckets which operate in the other pump chamber to pump and compress gas therethrough by the displacing action of these blades cooperating with an elliptical shaped casing formed by the walls of said other chamber having close clearance with the periphery of the rotor blades at the minor axis of the ellipse and with suitably placed cooperating inlet and outlet ports for the pumping and compression of gas therethrough by the displacing action of the elliptical casing on the circulated liquid ring.

HAROLD E. ADAMS.
